UNITED STATES PATENT OFFICE.

OTTO B. KLOETZER, OF COLUMBUS, OHIO.

COMBINATION COAL GRADING SCREEN AND PICKER TABLE.

1,032,612.

Specification of Letters Patent. Patented July 16, 1912.

Application filed January 26, 1912. Serial No. 673,601.

To all whom it may concern:

Be it known that I, OTTO B. KLOETZER, a citizen of Austria-Hungary, residing at Columbus, in the county of Franklin and 5 State of Ohio, have invented certain new and useful Improvements in Combination Coal Grading Screen and Picker Table, of which the following is a specification.

My invention relates to coal grading machines and is particularly directed to the provision of a combination coal grading screen and picker table.

It is designed to provide a screen grader and a picking table therefor, which not only 15 decrease the required space in a very great degree, but which render it possible to obtain what is termed "the run of the mine" with practically no preparation and at any time it may be desired, without changing 20 the normal course of the bulk of the material over the screening surfaces.

It is further aimed in the attainment of this result to finally distribute "the run of the mine" upon the picker table in two or 25 more layers with the bulk of the larger material in the uppermost layer and therefore subject to ready access by the pickers surrounding the table.

My invention preferably contemplates the 30 provision of a spiral oscillatory screen operating in conjunction with a rotary picking table preferably mounted upon a shaft forming the means of support of the spiral screen and desirably concentric therewith. 35 The spiral screen may be varied as to structural details, but it desirably comprises a plurality of successive sections of screen of determinately increasing mesh, each forming a false bottom for the body proper of the 40 chute. Beneath the terminus of each section, the bottom of the body portion proper of the chute is provided with a supplemental and laterally directed chute and each of these supplemental chutes has a gate there- 45 for normally raised, but capable of being lowered into the same plane with the floor or bottom of the body portion proper of the screen to close the opening to its chute.

When all of these gates are closed, the supplemental chutes are cut off and "the run of the mine" is permitted to pass down the entire length of the screen during the course of which passage the smaller material passes into the lower portion and slides along the 55 base of the body portion of the screen, while the larger proceeds to the end of the actual

screening surfaces. Thus "the run of the mine" would be delivered in layers to the picker table which is constantly rotating beneath the end of the oscillatory screen. 60

The preferred embodiment of my invention is shown in the accompanying drawings, in which similar characters of reference designate corresponding parts, and in which—

Figure 1 is a top plan view of my screening structure, and, Fig. 2 is a side elevation of the structure showing the relative positions of the vibratory oscillating screen and the picking table.

In the drawings, there is shown the vertical shaft 1 journaled at its base in the casting 2 and having its upper end provided with a beveled gear 3 with which meshes a bevel pinion 4 upon the end of a shaft 5 carried in bearings 6 which may be mounted 70 upon timbers as shown at 7. Between these timbers if such method of mounting is used, the shaft 5 carries a sprocket 8 which is driven by means of a chain 9 extending over a gear 10 upon the driving shaft 11 mounted 80 upon the adjacent framework 12, such shaft 11 carrying a pulley 13 which is driven as is customary and carrying at its ends crank arms 14 to which are connected links 15.

Keyed to the shaft 1 at a point comparatively near its base is a table-like structure 16 which is adapted and constructed to rotate therewith and which is supported near its outer periphery by spaced stanchions 17 having roller bearings 18 upon their upper 90 ends bearing against and supporting the track surface 19 upon the under surface of the table-like structure 16 at the outer periphery thereof. It will be understood from this that the driving of the pulley 13 drives 95 the shaft 11, sprocket 10 and by means of chain 9 drives the sprocket 8, which in turn rotates the shaft 5 and by means of the intermeshing connection of the bevel gear 3 and pinion 4 rotates the shaft 1 carrying the 100 table-like structure therewith. Thus the table-like structure which is known generally as the picker table, is continuously and positively rotated.

The shaft 1 is desirably provided at intervals with collars 20 and these collars serve as supports for spider arms 21 which support a spiral chute 22 of channel form and having a false bottom 23 of reticulate material arranged in successively increasing 105 grades, that is, with its apertures disposed in sets which are successive and in such suc-

cessive sets increase so that material passing down this false bottom is suitably graded in a manner known. At or near the end of each set of apertures in this false bottom, 5 the bottom proper of the chute is provided with a supplemental chute laterally directed and designated 24. The entrances to these laterally directed chutes are controlled by pivoted gates 25 which are normally in the 10 position of the gate shown at A in Fig. 2, but which may be lowered to the position of the gate shown at B in the same figure. When in the position shown at A, the material is graded into the grades for which 15 the screens are provided such as, for instance, egg, nut and lump, and these respective grades are directed into the laterally disposed chutes and delivered at the desired points. However, when it becomes desirable 20 to attain "the run of the mine" the valves or gates are closed by movement into position shown at B. The material then passes down along the false bottom of the spiral chute and along the actual bottom thereof. 25 The finer material necessarily passes into the actual base of the chute, while the extremely heavy material is maintained upon the top of the screen. Thus the material is delivered from the end of the chute upon the 30 rotating picker table in two distinct layers with the heavier material forming a large portion of the upper layer. Even in "the run of the mine" it is generally desirable to have the pickers work upon this heavier 35 coal and its position in the upper layer renders it very readily accessible. Of course, the operation is continuous under ordinary circumstances and there is provided means for brushing the material off the picker table just before completing one revolution 40 and passing it into any suitable receptacle or otherwise disposing of it.

The screening operation of the spiral screen is greatly facilitated by the connection thereto of the links 15 as at 15^a and 45 of course the continuous rotation of the

shaft 11 causes the transmission of the oscillatory movement to the spiral screen.

It will be seen that I have provided an extremely simple and compact structure for 50 grading coal, which may be readily transformed into a direct delivery device for the entire run of the mine. In addition, I have greatly minimized the required space in machines of this type by providing a rotary 55 picker table in combination with an oscillatory spiral screen oscillating about the shaft with which rotates the picking table.

What I claim, is—

1. A combination coal grader screen and 60 picker table comprising a spiral grading element, a rotating receiving element disposed beneath said spiral element, and means for eliminating the grading action of the spiral element.

2. A combined coal grader screen and 65 picker table comprising a rotary picker table, a spiral screen element having a false bottom of reticulate material in sets of varying meshes, means for conducting the material selected by each set of meshes, and means for rendering said conducting means ineffective whereby the entire bulk of material placed upon the spiral element is delivered at its lower end on to the picker 70 table.

3. A combined coal grader screen and 75 picker table comprising a screening element, a picker table beneath the delivery end of said screening element, the delivery end and 80 the said table being relatively rotatable, means for grading the material passing over the said screening element, and means for rendering said grading means ineffective to permit delivery of the entire bulk of mate- 85 rial to the picker table.

In testimony whereof I affix my signature in presence of two witnesses.

OTTO B. KLOETZER.
